UNITED STATES PATENT OFFICE.

OTHO M. OTTE, OF JAMESTOWN, NEW YORK.

SPOT-LIGHT MOUNTING.

1,324,615.

Specification of Letters Patent. Patented Dec. 9, 1919.

Application filed April 4, 1919. Serial No. 287,582.

To all whom it may concern:

Be it known that I, OTHO M. OTTE, a citizen of the United States, residing at the city of Jamestown, in the county of Chautauqua and State of New York, have invented certain new and useful Improvements in Spot-Light Mountings, of which the following, 5 taken in connection with the accompanying drawings, is a specification.

10 The invention relates to mounting for lamps for automobiles and other vehicles, and particularly for spot lights; and the invention consists in providing a simple bracket attachment having means on its 15 outer end upon which a lamp supporting standard may be mounted so as to be rotatively adjustable either vertically or horizontally, said standard comprising a pair of clamping plates which support a fixed 20 source of light in relation to a movable reflector, and means for slidably adjusting the relation of said reflector to said fixed source of light by moving backward or forward along the common axis of both; and second, 25 to provide a two-part switch housing on the rear end of a tubular rear extension on said reflector which may be locked permanently in position by means of plugs removably attached to said switch by passing through 30 coinciding openings in the two parts of said switch housing, thereby also providing a bulb shaped handle for the quick and positive control in the adjustment of the lamp; and the invention consists in the novel features and combinations herein set forth and 35 claimed.

In the drawings, Figure 1 is a side elevation of the improved lamp mounting supporting the rearward extension of my reflector lamp, portions being broken away to 40 show the construction. Fig. 2 is a sectional view of Fig. 1 of the upper portion of the standard and rear lamp extension and an elevation of the lower portion of said standard, showing the disk shaped upper end of 45 said lower portion clamped by said upper portion. Fig. 3 is a sectional view of a portion of the casing of the lamp showing part of said tubular extension and the manner 50 of adjusting the focus of the electric bulb light. Fig. 4 is an elevation of the rear extension tube of the lamp showing the focus adjusting slot therein. Fig. 5 is a detail 55 of the electrical connection of the lamp showing the arrangement of the wiring of 60

the push switch. Fig. 6 is a perspective view of modification of the three-part lamp standard for clamping said rearward extension of the lamp. Fig. 7 is a sectional view of said modification showing the construction and arrangement of the same. Fig. 8 is a perspective view of one of the clamping plates; and Fig. 9 is an edgewise elevation of one of said clamping plates with slight modification in which the clamping 65 screw is cast as a part of said plate. Fig. 10 is a perspective view of the lower standard part.

Like characters of reference refer to the corresponding parts in the several views. 70

The numeral 10 designates the bracket which preferably has the threaded pin end 11 to receive the lower part 12 of the lamp supporting standard around said pin 11 through a hole in said part 12. 75

The upper portion of said lamp supporting standard consists of two clamping plates 13 and 14 which fit around the disk shaped upper end 15 of the part 12, the clamping action being attained by means of the screw 80 16. The plates 13 and 14 are arranged to clasp around the tubular rear extension 17 of the reflector 28 by means of oppositely outwardly curved portions, said plates 13 and 14 extending above the rear tubular extension 85 17 to receive therethrough a second clamping screw 18. A slot 19 is provided in the rear extension 17 to receive therethrough the set screw 20, which set screw 20 is preferably threaded in the clamping plate 13 90 or 14, for it may be on either side of the upper portion of said standard, and has a slip fit in the inner socket sleeve 21 and insulation plug 22 through which the two connecting wires 23 and 24 extend to the contacting points 25 and 26 on the butt of the lamp 27 since the sleeve 21 and plug 22 need only to be held stationary in relation to the clamping plate 13 and without compression so that the tubular rear extension 17 and reflector 28 attached thereto may be adjustably slipped back and forth with set screw 20 in the slot 19, in adjusting the focus of the lamp 27 to said reflector 28, it only being necessary to release the two clamping screws 105 16 and 18 for the clamping plates 13 and 14 to permit the back and forth adjustment of the tubular rear extension 17 and the lamp reflector 28 attached thereto, the lamp 27 remaining fixed in its position as held by 110

the set screw 20, said set screw 20 only being released or removed when it is desired to take apart the entire lamp.

The modification shown in Figs. 6 to 10 has two clamping plates 29 and 30 which engage around the rearward extension 17 of the reflector 28 in substantially the same manner as in the preferred form of standard shown in Figs. 1 to 5, having a screw 18 above the tubular extension 17 and a set screw 38, the same as the clamping plates 13 and 14. The outer end 31 of the bracket 10 is provided with a horizontally flat portion having a hole therethrough to receive the downwardly projecting screw pin 32 with the washer 33 and nut 34 thereon. The upper end 35 of the lower part 36 is flat and disk shaped and has the hole 37 therethrough to receive the clamping bolt or screw 38 through the hole 39 in the disk shaped lower ends 40 of the clamping plates 29 and 30 to thereby adjustably clamp the flat sides of the disk 35.

It is apparent that the modification has the double clamping plates and may be adjusted both horizontally and vertically the same as the preferred form of standard with its lower portion 12 and clamping plates 13 and 14 as shown in Figs. 1 and 2. Said form as shown in Figs. 1 and 2 is preferred because of the ease with which the plates 13 and 14 may be clamped upon the beveled disk shaped upper end 15 of the lower part 12, the screw 16 holding said clamping portions 13 and 14 firmly in position thereon with a small amount of force in comparison with the force necessary to clamp the disk shaped ends 40 on the opposite sides of the disk 35 in part 36.

40 The rearward extension comprises the tube 17 and switch casing 41 which is attached on the rear end of the part 17 by screw 42. The push switch 43 is provided with removable pins 44 so that the ring 45 containing the switch mechanism may be inserted within the rear end of the switch casing 41 and the metal cap 46 may be placed over the rear end of the switch casing 41, said cap 46 and switch casing 41 having holes 47 in the opposite sides into which the removable pins 44 may be inserted and attached in the ring of the switch 43 preferably with a slip socket joint. This arrangement permits the quick and easy assemblage 55 or dismemberment of said rearward extension to adjust the wiring or for repairing the parts. At the same time the bulb formed by the switch case 41 and cap 46 forms a convenient bulbous shaped handle by which 60 the lamp can be turned in any direction, the extension 17 giving sufficient leverage for said adjustment. The electric lamp 27 is connected directly to the source of electrical energy by the positive wire 24 and the negative wire 23 is broken by the push switch

43 so as to turn the light on or off as desired. It will be noted that the plug 22 and inner socket sleeve 21 are held in definite relation by means of the set screw 20. This position of the electric bulb lamp 27 is maintained at all times after the lamp is assembled, and the focusing of the lamp is accomplished by sliding the reflector 28 and the tube 17 backward or forward as desired, it only being necessary to slightly loosen the clamping screws 16 and 18 to permit said sliding action of said tube and reflector.

I claim as new:

1. In a lamp mounting, in combination with a lamp having a rear extension, a bracket, a standard-like member adjustable in a vertical plane borne by the bracket and having a horizontal disk on its upper end, a pair of opposed clamping members formed to clampingly engage over the periphery of the disk at their lower portions and formed to clampingly engage over the lamp extension at their upper portions, and means to secure the pair of clamping members in clamping relation to the disk and lamp extension.

2. In a lamp mounting, in combination with a lamp having a rear extension, a bracket, a lower standard-like member borne by the bracket and having a disk, an upper sectional clamping member clamped at one end about opposite sides of the disk and at its other end about the lamp extension, means to permit one of the members to be rotatively adjusted in a horizontal plane, and means to permit the other member to be adjusted in a vertical plane.

3. A mounting for lamps comprising a bracket, a lamp having a rear extension thereon, a three-part connection between said lamp and bracket consisting of a lower portion pivotally attached on said bracket and having a disk at its upper end, and two clamping plates rotatively adjustable on said lower portion at right angles to the plane of rotation of said lower portion on said bracket to clamp both said disk on said lower portion at one end of the plates and said rear extension of said lamp at the other end of the plates.

4. In a lamp mounting, in combination with a lamp having a rear extension thereon, a bracket having a threaded pin on its outer end, a three-part connective standard rotatively mounted on said pin having means to hold the same in an adjusted position, a disk shaped upper end on the lower portion of said standard, and clamping plates rotatively attached to said disk shaped upper end of said lower portion of said standard and clamping around said rear extension of said lamp to adjustably hold said lamp in different positions.

5. In a lamp mounting, in combination with a lamp having a rear extension there-

on, a bracket having a threaded pin on its outer end, a standard having a lower portion vertically rotatively adjustable on said pin, a horizontal disk on the upper end of said lower portion with a beveled edge, two plates one to each side shaped to clamp the beveled edge of said disk at their lower ends in horizontal rotative adjustment and around said rear extension of said lamp at the upper end, and suitable clamping screws for said plates.

6. In a lamp mounting, in combination with a lamp having a rear extension, a bracket, a lower standard-like member borne by the bracket and having a disk, an upper sectional clamping member clamped about the disk and about the lamp extension, means to permit one of the members to be rotatively adjusted in a horizontal plane, and means to permit the other member to be adjusted in a vertical plane, said lamp extension having a slot and the sectional clamping member having a part extending in the slot.

7. In a mounting for lamps in combination with a reflector lamp having a tubular slotted rear extension on the reflector of said lamp, a plug and electric lamp socket sleeve in said slotted tubular rear extension, a support for said lamp engaging said

slotted tubular rear extension, a set screw in said support extending through said slotted tubular rear extension and engaging said plug and socket sleeve to hold the same in fixed relation to said support while permitting a back and forth adjustment of said reflector to said lamp without moving said lamp.

8. In a mounting for lamps, a bracket, a standard adjustably attached on said bracket, a reflector lamp having a tubular rear extension thereon, two plates and screws on said standard to clampingly engage said rear extension of said lamp to support the same, a plug and electric lamp socket sleeve in said tubular rear extension of said lamp, a set screw in one of said plates to hold said plug and socket sleeve in fixed relation thereto, said tubular rear extension having a slot therein for said set screw to permit the adjustment of said reflector to said lamp without moving said lamp socket sleeve and plug.

In testimony whereof I have affixed my signature in the presence of two witnesses.

OTHO M. OTTE.
